(57) **CLAIM**

The ornamental design for a vehicle front chin splitter with Sapphire logo, as shown and described.

DESCRIPTION

FIG. 1 is a top, front and right side perspective view of a vehicle front chin splitter with Sapphire logo, of our new design;

FIG. 2 is a bottom, front and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is an enlargement of a central portion of the top plan view of the vehicle front chin splitter with Sapphire logo. The broken lines in the drawings illustrate portions of the vehicle front chin splitter with Sapphire logo, as well as a boundary of the enlargement in FIG. 9, that form no part of the claimed design.
